UNITED STATES PATENT OFFICE.

HARRISON WOODMANSE AND JOHN AUE, OF FREEPORT, ILLINOIS; SAID
AUE ASSIGNOR TO SAID WOODMANSE.

TOWER FOR WINDMILLS.

SPECIFICATION forming part of Letters Patent No. 641,250, dated January 9, 1900.

Application filed April 24, 1899. Serial No. 714,244. (No model.)

To all whom it may concern:

Be it known that we, HARRISON WOODMANSE and JOHN AUE, citizens of the United States, residing at Freeport, in the county of Stephenson and State of Illinois, have invented 5 certain new and useful Improvements in Towers for Windmills, of which the following is a specification.

The object of this invention is to so construct and equip windmill-towers with brace- 10 rods and tighteners that they may be conveniently and securely braced when erected and readily rebraced at any time thereafter; and it consists of certain new and useful features 15 of construction and combinations of parts hereinafter fully described, and specifically pointed out in the claim.

Referring to the accompanying drawings, 20 which form a part of this specification, Fig. 1 is a side elevation of a section of a windmill-tower embodying our improvements. Fig. 2 is a side elevation of a brace-rod and a 25 tightener of the tower in enlarged detail. Fig. 3 is a top plan view of the same. Fig. 4 is a section at the line 4 in Fig. 2 of the parts there shown.

Like letters of reference indicate corresponding parts throughout the several views.

A are angle-iron corner-posts of the wind- 30 mill-tower.

B are angle-iron cross-girds securely connecting them together.

C are crossed brace-rods (attached at their 35 opposite ends by means of bolts or rivets D to adjacent and opposite corner-posts A) drawn tensely by applying force to their middle portions and forcing them in opposite directions in a plane parallel to their points of attachment D.

E are tighteners having slots E' therein to 40 admit the edge of the angle-iron cross-girth B,

provided with jaws E² for clamping the crossed brace-rods C when drawn tensely, as shown in Fig. 1, securely against the same and furnished with set-screw openings E³ therein. 45

F are set-screws for securing the tighteners E in position on the cross-girds B.

After the parts of the tower have been put together in the manner already indicated the brace-rods C are forced simultaneously in opposite directions until they are as tense as desired and are then secured in such tense condition to the contiguous cross-girth B. Fig. 1 shows the brace-rods C forced outward. They may be forced inward with identically the 55 same results. Obviously whenever it is desired at any time to retighten any or all of the brace-rods C it can be done with ease and despatch.

What we desire to claim and secure by Letters Patent is—

In a windmill-tower, in combination, angle-iron corner-posts, angle-iron cross-girds securely connecting them together, crossed brace-rods—attached by their opposite ends to 65 adjacent and opposite corner-posts—tensely drawn, by applying force to their middle portions and forcing them in opposite directions, in a plane parallel to their points of attachment, and tighteners having slots therein, to 70 admit the edge of the angle-iron cross-girth, and provided with jaws for clamping the crossed brace-rods to such cross-girth, and set-screws for securing said tighteners in position on the cross-girth, substantially as and for the 75 purpose specified.

HARRISON WOODMANSE.
JOHN AUE.
